Leo J. Du Mais, Chicago, and Chester C. Cooley
and John T. Heck, Elmhurst, Ill., assignors to
Da-Lite Screen Co., Inc., Chicago, Ill., a corpo-
ration of Illinois

Application August 24, 1946, Serial No. 132,796

Term of patent 14 years

(Cl. D61—1)

To all whom it may concern:

Be it known that we, Leo J. Du Mais, Chester C. Cooley, and John T. Heck, citizens of the United States, said Du Mais being a resident of Chicago, county of Cook, State of Illinois, and said Cooley and Heck both being residents of Elmhurst, county of Du Page, State of Illinois, have invented a new, original, and ornamental Design for a Casing for Picture Projection Screen, of which the following is a specification, reference being had to the accompanying drawing, forming a part thereof.

Fig. 1 is a perspective view of a casing for picture projection screen, showing our new design.

Fig. 2 is an end view of the same.

Figs. 3-6 are elevational views of same showing the front, bottom, back and top thereof, respectively.

We claim:

The ornamental design for a casing for picture projection screen, substantially as shown.

LEO J. DU MAIS.
